UNITED STATES PATENT OFFICE.

RILEY H. HOWARD, OF BROOKLYN, NEW YORK.

OIL-BURNER AND OIL-BURNING STOVE.

SPECIFICATION forming part of Letters Patent No. 325,413, dated September 1, 1885.

Application filed June 18, 1884. (No model.)

To all whom it may concern:

Be it known that I, RILEY H. HOWARD, of the city of Brooklyn, in the county of Kings and State of New York, have invented a new 5 and useful Improvement in Oil-Burners and Oil-Burning Stoves, of which the following is a specification, reference being had to the accompanying drawings, forming part of the same, in which—

10 Figure 1 is a front elevation of a stove containing my improvement, together with my improved oil-burner. Fig. 2 is a plan view of the bottom plate of my burner to be particularly described; and Fig. 3 is a longitudinal 15 vertical section of my burner and the oil can or holder with which the burner is connected, the section being on line $x x$, Fig. 2.

15 My invention relates to a burner for burning kerosene or other volatile hydrocarbon 20 particularly as a fuel in stoves; and it consists, first, in the combination of the wick-tube and devices for elevating and lowering the wick 25 therein with the top of the lamp or oil-fount herein described, whereby the heating of the oil in the fount through the medium of the wick-tube is to a large extent avoided; and, second, in the combination of my burner with a stove or range.

30 A represents an oil can or fount, in an opening in the top of which the burner is secured. This fount may be rectangular in form, the length about twice the width, and the depth about one-third of the width, as represented in Figs. 2 and 3. This form, and the 35 relative dimensions stated, adapt the fount properly to the space and place it is designed to occupy in the stove, as represented in Fig. 1.

35 The burner is composed of two plates, B and C, the plate B covering the opening in the top 40 of the fount, and secured thereto in any suitable manner. It is provided with openings a , for the passage through the plate of the wick-tubes, one of which is shown at b , Fig. 3. These openings are considerably broader than 45 the cross-section of the wick-tube through their entire length excepting near their ends, where they are narrowed, as at c , Fig. 2, to the thickness or cross-section of the tube so that the tube on being passed through these 50 openings will be in contact with the said plate only at the points c .

On the plate B is an upwardly-extending

flange, d , carried across the ends of the plate B, and also the sides a little distance inward from their edges. In the upper edges of the longitudinal portions of this flange notches e are made, which constitute bearings for the rods or shafts (one of which is shown at f , Fig. 2) that carry the spur-wheels g , for raising and lowering the wick in the tubes. The shafts f are supported at each end in sleeves $h h'$, in which the rods may freely turn, the said sleeves resting in the notches e without motion. The wick-tubes b are rectangular in form, the horizontal breadth equaling the length of the 55 openings a in plate B, or nearly so, and of vertical length sufficient to extend below the plate B, and far enough above plate C to enter the cones D. The plate C is also provided with openings i , through which pass 60 the wick-tubes, and rests down upon the flange d on plate B, so that the openings in the two plates shall be vertically coincident, and plate C is secured to plate B by screws $j j'$. The flange d is of sufficient width or depth to 65 provide an air-chamber between B and C, through which the air may circulate, whereby the plate B is kept cool. The wick-tubes are soldered fast to the sleeves $h h'$, and are thus supported vertically on the rod or shaft f , 70 while the shaft is left free to revolve or rotate in the said sleeves. Openings are made in the side of the wick-tube through which the spur-wheels g project to engage with the wick in the tube. The said shafts f are provided 75 at one end with buttons or finger-pieces, as shown at f' , Fig. 2, for the convenient turning of the shafts for raising and lowering the wick.

80 The plate C has the form shown in cross-section at Fig. 3—that is to say, the plate is raised at the openings i , the raised portion forming segments of hollow cylinders extending nearly across the plate, thus providing 85 housings r for the spur-wheels g , or spaces 90 within which they may revolve, and carrying the points of contact between the wick-tube and the plate C farther away from the plate B than would be the case if the plate C were 95 plane, and thus decreasing the liability of the plate B to become heated by heat communicated from the wick-tube to the plate C.

100 E is a perforated metal screen rectangular in form and of suitable dimensions to fit down

tightly over a flange, *k*, on the plate C. This screen is provided with openings *l*, through which pass the wick-tubes, as shown in Fig. 3. The cones D rest down upon and are supported by said screen.

Fig. 1, as before stated, represents a front view of a stove or range constructed and adapted to receive the above-described burners and fount. It is intended to represent a stove with the usual fire-place and ash-pit, the burner and fount being intended to be placed in the ash-pit immediately underneath the fire-place. To this end the sides F F of the stove are provided with ribs or inwardly-projecting flanges *m m'* near the bottom edge of the said sides, and also with shoulders *n n'*, and so constructed and arranged that the fount A may be passed into the stove between said flanges and shoulders and rest upon the flanges.

The upper edge of the front opening into the ash-pit and to the fire-place is formed as represented in Fig. 1 at *p*, the center part being carried up above the ends, leaving a space through which the cones of the burners may pass, the door G being made to extend down to the lower line of the said opening, and when shut to close in the said cones.

Now, it is evident that in a burner thus constructed there is very slight contact between the wick-tubes and the plates B and C, the wick-tubes being entirely detached from both so that comparatively little heat is communicated from the burning wick through the

tubes to the plates covering the fount, thus obviating, in a great degree, the liability of heating and vaporization of the oil in the fount, while suitable provision is made for supporting in a fixed position the wick-tubes extending down into the fount and up into the cones, and also for raising and lowering the wicks in the tubes.

Another and important advantage of this arrangement of the wick-tube is the facility it affords for removing a worn tube for repairs or to replace it with a new one without the inconvenience attending such operations in stoves as usually constructed.

What I claim as my invention and desire to secure by Letters Patent, is—

1. In an oil-burner, the wick-tube detached from the cap or covering of the fount and attached to a wick-shaft sleeve that rests upon and is supported by the cap or covering of the oil-fount.

2. In an oil-burner, the combination of a plate provided with an opening, *a*, and flange *d*, the plate C, provided with the opening *i*, formed with the housing *r*, the wick-tube *g*, the sleeves *h h'*, to which the wick-tube is secured, and the shaft *f*, provided with the spur-wheel *g* and fitted to turn in the said sleeves, which rest upon and are supported by the said flange *d*.

RILEY H. HOWARD.
